HEATER WITH DRAFT CONTROL

Filed Oct. 8, 1928

JOS. B. SMITH,

334 *B. Mallinckrodt.* Attorney

UNITED STATES PATENT OFFICE

JOSEPH B. SMITH, OF SALT LAKE CITY, UTAH

HEATER WITH DRAFT CONTROL

Application filed October 8, 1928. Serial No. 310,935.

This invention relates to a draft control for heaters and is particularly applicable to brooder stoves where a very close regulation of heat is required, though its utility is not restricted thereto. The invention embodies additions and improvements for those stoves forming the subjects of my U. S. Patents Numbers 1,642,565 and 1,700,183.

The principal objects of the present invention are to provide:

First, A heater wherein the fire shall be regulated by means of draft passages controlled by a series of dampers which are operably interconnected with each other.

Second, A series of interconnected dampers controlled in common, automatically, by thermostatic means.

Third, Means for adjusting the various dampers so that their movements relatively to one another may be varied within comparatively wide limits.

Fourth, An apparatus which shall be simple, efficient and economical.

The features for which the protection of Letters Patent is desired, are collectively grouped in the claims concluding this specification.

In the drawing, which illustrates one embodiment of the invention,

Fig. 1 represents a vertical center section taken from front to back;

Fig. 2, a vertical section taken principally on line 2—2, Fig. 3, parts in the foreground and within the offset broken line, being shown in elevation.

Fig. 3, a top plan;

Figs. 4 and 5, fragmentary portions of Figs. 1 and 2 respectively, showing alternate positions of parts;

Figs. 6, a fragmentary portion of Fig. 1 substantially included within the broken line 6 and drawn to an enlarged scale;

Fig. 7, a front elevation corresponding to Fig. 6; and

Fig. 8, a plan partly in section on line 8 in Fig. 7.

While the representation of a brooder stove in the present drawing varies from the representations in my U. S. patents hereinbefore mentioned, yet the component parts of the stove proper, in the different drawings, are representative of one another.

Referring to the present drawing, 20 indicates the body of the stove supported on the base 21, surrounded by the duplex drum 24, mentioned in my said Patent No. 1,700,183. Extending along the sides of the stove from top to bottom, and preferably diametrically opposite each other, are defined the down draft passages 25. These lead into the ash chamber 26 beneath the grate 27 and are open at the top. Extending into the fire chamber 30 from the top 29 and having an inlet mouth 31—1, is the hot blast conduit 31.

Rigidly supported on the top 29 are the standards 32 and 34 in which are fulcrumed twin levers 35 and 36, respectively, these being in operative engagement with each other and with the yoke 37, for instance, by means of the pivot pin 38. The twin levers may also be called down draft levers. To the yoke may be pivoted the lower ends of links 39, whose upper ends may be pivoted at 40 to the lever 41, which may be rigidly attached to the plate damper 42. Damper 42 may be pivoted at 45 in the smoke flue 43, the latter being preferably mounted on the top 29. The damper 42 bears against the coating damper 46, the latter having the smoke opening 47 and the opening 48 for air from the room in which the heater is located. The closed position of dampers 46 and 42 is shown in Fig. 1, and the extreme open position, in Fig. 4.

Loosely held in the lever 41 is the connecting rod 48. This rod may be threaded to carry the adjusting nuts 49 and 50 capable of being variously positioned along the rod so as to give not only a variable action be-

5 between the rod 48 and the lever 41, but also to vary the length of the rod between the nut 49 and the pivot pin 51, by which latter the lower end of the connecting rod is fastened to the lever 52. The lever 52 may also be called hot blast lever and may be fulcrumed at a convenient point, for example, the pivot 53 carried in the standards 54.

10 In the opposite end of the lever 52 may be loosely carried the threaded stem 56 attached to the damper 57. On the stem 56 is an engaging member such as the adjustable wing-nut 58 which allows the end of the hot blast lever to have a certain amount of motion, or else no motion at all, relatively to the damper 57.

15 In the outer extremities of the levers 35 and 36 are loosely carried the threaded stems 59, which at their lower extremities are attached to the dampers 60. Engaging members, such as wing nuts 61, adjustably positioned on the stems 59, permit the travel of the levers 35 and 36 relatively to the dampers 60, to be varied as desired from zero to maximum.

20 A master lever 62 may be connected to the system of levers previously described, by mounting one end thereof on the previously mentioned pin 38. The master lever may be 25 fulcrumed at a convenient point, such as 63 in the standards 64, so as to give the desired ratio of motion to the said lever system. To the opposite end of the master lever may be adjustably fastened by a wing nut 71, one end 30 of rod 67 which extends to the movable member 68 of the thermostat 69.

25 When the thermostat imparts downward movement to the rod 67, the outer extremities of the levers 35 and 36 are depressed, thereby 40 tending to close the dampers 60 when the wing nuts 61 are in the positions relatively to stems 59, as shown. However, as the nuts 61 are screwed upward on the stems 59, it is possible to prevent the dampers 60 from receiving any motion from the levers.

30 The same motion of the levers 35 and 36 causes the yoke 37 to be lifted, thereby pushing upwardly on the links 39, and causing the lever 41 to be raised. This brings the 35 dampers 42 and 46 ultimately to the positions shown in Fig. 4. Simultaneously, the stem 48 is pulled upwardly, thus depressing the forward end of the bent lever 52 and causing the damper 57 to be seated on the inlet 45 to the hot blast conduit 31. When the lever 41 moves downwardly, due to its over-balance, it bears on the nut 49 as shown in Fig. 1, and causes the damper 57 to be lifted from its seat.

50 By means of the nuts 49 and 50 on the stem 48, and by means of the nut 58 on the stem 56, the relative motions of the dampers 42 and 46, and of the damper 57, may be adjusted to suit the required conditions.

55 The extended arm 70 of the lever 41 may

be made of sufficient length to counterbalance the master lever 62 with its rod 67, and the various dampers. The fulcrums of the various levers are positioned as desired, to give the proper ratio of movement to the damper 70 assembly.

60 The hover 72 may be similar to the one shown in U. S. Patent No. 1,700,183.

65 The various pivot bearings may be made rather loose so as to allow sufficient play for 75 the movement of the levers.

70 While a specific embodiment of my invention is herein shown and described, it is to be understood that various changes could be made therein without departing from the 80 spirit and scope of the invention as defined in the claims.

75 Having fully described my invention, what I claim is:

1. A heater having in combination, a fire chamber, down draft conduits leading into space below the fire chamber, a hot blast conduit leading into the upper part of said fire chamber, a dampening opening defined in the smoke flue of said heater, dampers for 85 said down draft conduits, a damper for said hot blast conduit, a damper for said dampening opening, a system of interconnected operating levers, and individual adjusting devices between said dampers and the respective operating levers. 90

2. A heater having in combination, down draft conduits, a hot blast conduit, a smoke flue with pivoted coacting dampers therein, an arm protruding rigidly from one of said pivoted dampers, a damper for said hot blast conduit, a lever for the hot blast damper, a connecting rod extending adjustably from said hot blast lever to said arm, twin levers connected to said arm, and dampers for said down draft conduits adjustably mounted on 100 said twin levers. 105

3. The combination with a heater, of twin levers fulcrumed on said heater, a smoke flue having coacting plate dampers mounted 110 therein, an arm extending from one of the plate dampers, a flexible connection between said twin levers and said arm, a hot blast conduit extending into said heater, a damper for said hot blast conduit, a lever operative upon said hot blast damper and an adjustable connecting rod extending from the last mentioned lever to said arm. 115

4. The combination with a heater, of twin levers fulcrumed on said heater, a smoke flue having coacting plate dampers mounted 120 therein, openings defined in one of said plate dampers, an arm extending from the other said plate damper, a flexible connection between said twin levers and said arm, a hot 125 blast conduit extending into said heater, a damper for said hot blast conduit, a lever operative upon said hot blast damper and an adjustable connecting rod extending from the last mentioned lever to said arm. 130

5. A heater having in combination, a fire chamber, down draft conduits leading into space below the fire chamber, a hot blast conduit leading into the upper part of said fire chamber, a damper in the smoke flue of said heater, down draft dampers, a hot blast damper, a system of interconnected operating levers, individual adjusting devices between said dampers and the respective operating levers, a master lever connected to said operating levers, and a thermostat operative upon said master lever.

In testimony whereof, I sign my name hereto.

15

JOSEPH B. SMITH.
